[57] CLAIM

The ornamental design for a watch bracelet, as shown.

DESCRIPTION

FIG. 1 is a top plan view of a watch bracelet showing my new design;

FIG. 2 is a side elevational view;

FIG. 3 is a bottom plan view; and,

FIG. 4 is an opposite side elevational view to that shown in FIG. 2.

The broken line showing of a watch in FIGS. 1-4 is for illustrative purposes only and forms no part of the claimed design. It being understood that the bracelet is continuous.
